(57) **CLAIM**

We claim the ornamental design for a wireless control device, as shown and described.

DESCRIPTION

FIG. 1 is a perspective view of a wireless control device according to our new design.

FIG. 2 is a bottom view thereof; and,

FIG. 3 is a side view thereof.

The wireless control device is rotationally symmetric, so the front, right side, left side and rear views are equivalent. The top view forms no part of the design and is omitted. The portions of the drawings appearing in broken line are for environment only and do not form a part of the claimed design.
